Attorney.

UNITED STATES PATENT OFFICE.

FREDERICK SIEMENS, OF DRESDEN, SAXONY, GERMANY.

GAS-LAMP.

SPECIFICATION forming part of Letters Patent No. 313,779, dated March 10, 1885.

Application filed January 25, 1884. (No model.) Patented in Germany October 16, 1883, No. 28,105; in England November 26, 1883, No. 5,520; in France December 3, 1883, No. 158,939; in Belgium December 4, 1883, No. 63,431, and in Austria-Hungary April 27, 1884, No. 10,259 and No. 18,518.

To all whom it may concern:

Be it known that I, FREDERICK SIEMENS, a citizen of Saxony, residing at Dresden, in the Empire of Germany, have invented a new and useful Improvement in Gas-Lamps, (for which I have obtained provisional protection in Great Britain, No. 5,520, dated November 26, 1883, and made applications in France and Belgium, dated, respectively, December 3, 1883, and December 4, 1883,) of which the following is a specification.

The heat radiated from a gas-flame depends to a great extent upon its luminosity, and the luminosity itself depends in great measure on the heat of the air and gas that combine in the act of combustion.

My invention relates to a construction of gas-lamp by which I obtain so high a degree of luminosity that I can afford to shroud part 20 of the flame by an appliance for heating the air and gas, this heating constituting the means by which so high a degree of luminosity is attained that the light given by the unshrouded part of the flame is greater than would otherwise be obtained from the whole flame if it were destitute of the heating appliance.

I will describe the construction of the lamp which I adopt, referring to the accompanying drawings.

30 Figure 1 is a vertical section, and Fig. 1^a a sectional plan, of my lamp in its simple form; and Fig. 2 is a vertical section, and Fig. 2^a a sectional plan, of the lamp somewhat modified for larger sizes.

35 The gas arriving by the pipe R enters a chamber, g, from which it rises by a number of small tubes, r, arranged in a circle. Surrounding these tubes and extending some distance above them is a casing, l, having at its lower part a number of holes and slits, t and t', for admission of air. The upper part of the casing l preferably terminates with a turned-in lip, a, and around the interior of the casing are a number of ribs, p, projecting inward.

45 In the center of the burner is a stem, s, made with projecting ribs p', and terminating with a conical head, n. The glass chimney x is supported on several brackets, f, projecting from the casing l. The flames of the gas issuing 50 from the tubes r radiate heat to the casing l

and to the stem s, the ribs p and p' of which expose extended surfaces, and the air entering by the holes and slits t and t' becomes highly heated as it ascends in contact with these heated surfaces. The gas is also heated by the heat conducted down the casing, stem, and tubes, and thus a flame of great intensity is produced, with illuminating-power so great that the part of it which appears above the casing gives greater light than the whole flame would give 60 if no part of it were shrouded by a casing arranged to heat the air-supply. The lip a of the casing and the head n of the stem by directing the ascending current of heated air against the outside and inside of the cylindrical 65 flame cause great intensity of light above the casing.

I am aware that annular caps of conical or convex form have been heretofore so constructed as to rise a little higher than the hub of the 70 burner for the purpose of deflecting air upon the flame or steadyng it.

I am also aware that in the German Letters Patent No. 18,884, of the year 1882, heretofore granted to me, a burner is described in which 75 the casing of one of several sets of tubes reaches some distance above the top of an outer ring of tubes; but it is to be remembered that the flame from the latter is entirely inclosed by the casing and does not operate as a part of the 80 illuminating-flames of the lamp, as in my present invention, but serves entirely for heating purposes. When the lamp is made of small size, where the area for passage of air is limited, the ribs p p' may be dispensed with. For 85 lamps of larger size the construction may be modified, as shown in Figs. 2 and 2^a. In this case the central stem, s, is made tubular, with slits t' at its lower part for admission of air to its interior and with its upper lip, n, curved 90 outward. Within it is a gas-tube, r', the flame from which heating the stem increases its power of heating the air passing upward between it and the casing l.

In the drawings the gas entering the chamber g is represented as rising through a number of small tubes, r, arranged in a circle. It will be obvious, however, that without departing from my invention these tubes may be arranged in such a manner as to form an 100

ellipse or other suitable figure, and that instead of using the tubes *r* to conduct the gas to the point of combustion any other suitable known devices may be used—as, for instance, an annular or Argand burner having holes arranged therein a certain distance apart for the escape of the gas.

Having thus described the nature of my invention and the best means I know of carrying it out in practice, I claim—

1. In a gas-lamp, the combination of a number of gas-jets with a relatively high central ribbed stem and a ribbed cylindrical casing, as and for the purposes described.
- 15 2. The combination of a number of gas-jets, a relatively high central stem, a cylindrical casing surrounding the tubes or jets and extending above them, and a chamber located above the gas-tubes and within the cylindrical casing in which the flames of the gas issuing from the jets are partially shrouded and the heat thereof is radiated to the casing.
- 25 3. The combination of the chamber communicating with the gas-pipes from which rise a number of small tubes or jets, a perforated casing surrounding the tubes and extending some distance above them, and a chamber located above the gas-tubes and within the cylindrical casing in which the flame of the gas issuing from the jets is partially shrouded and radiated to the casing.
- 30 4. In a gas-lamp, the combination of a num-

ber of gas-jets, a relatively high stem terminating with a conical head, a relatively high cylindrical casing, and a chamber located above the gas-jets and between the stem and the casing in which the flame of the gas issuing from the jets is shrouded and radiated to the casing.

35 5. In a gas-lamp, the combination of a number of gas-jets, a relatively high stem terminating with a conical head, a relatively high cylindrical casing terminating at its upper part with a turned-in lip and having in its lower part a number of slits, and a chamber located above the gas-jets and between the stem and the casing in which the flame of the gas issuing from the jets is shrouded and radiated to the casing.

40 6. In a gas-burner in which the gas issues in a series of small jets, a metal casing inclosing the lower part of the flame which serves to take up the heat of the flame and impart it to the gas and air supply, in combination with a chamber in which the flame of the gas issuing from the jets is shrouded.

45 55 In testimony whereof I have signed my name to this specification in the presence of two subscribing witnesses this 8th day of January, A. D. 1884.
